(57) **CLAIM**

The ornamental design for a snow density gauge, as shown and described.

DESCRIPTION

FIG. 1 is a front perspective view of a snow density gauge according to a first embodiment of the invention; the markings shown in FIG. 1 are merely exemplary.

FIG. 2 is a left side view of a snow density gauge according to a first embodiment of the invention.

FIG. 3 is a right side view of a snow density gauge according to a first embodiment of the invention.

FIG. 4 is a front view of a snow density gauge according to a first embodiment of the invention.

FIG. 5 is a rear view of a snow density gauge according to a first embodiment of the invention.

FIG. 6 is a bottom view of a snow density gauge according to a first embodiment of the invention.

FIG. 7 is a top view of a snow density gauge according to a first embodiment of the invention.

FIG. 8 is a left side view of a snow density gauge according to a first embodiment of the invention having a serrated front edge.

FIG. 9 is a right side view of a snow density gauge according to a first embodiment of the invention having a serrated front edge.

FIG. 10 is a bottom view of a snow density gauge according to a first embodiment of the invention having a serrated front edge.

FIG. 11 is a top view of a snow density gauge according to a first embodiment of the invention having a serrated front edge.

FIG. 12 is a front perspective view of a snow density gauge according to a second embodiment of the invention; the markings shown in FIG. 12 are merely exemplary.

FIG. 13 is a left side view of a snow density gauge according to a second embodiment of the invention.

FIG. 14 is a right side view of a snow density gauge according to a second embodiment of the invention.

FIG. 15 is a front view of a snow density gauge according to a second embodiment of the invention; and,

FIG. 16 is a rear view of a snow density gauge according to a second embodiment of the invention.

The broken line showing of markings is for the purpose of illustrating indicia and forms no part of the claimed design.
